ATTORNEY

UNITED STATES PATENT OFFICE.

DE WANE B. SMITH, OF DEERFIELD, NEW YORK.

DESIGN FOR A BODY FOR BICYCLE-PUMPS.

SPECIFICATION forming part of Design No. 28,271, dated February 8, 1898.

Application filed October 25, 1897. Serial No. 656,371. Term of patent 14 years.

To all whom it may concern:

Be it known that I, DE WANE B. SMITH, a citizen of the United States, residing at Deerfield, in the county of Oneida and State of New York, have invented and produced a new and original Design for a Body for Bicycle-Pumps, of which the following is a specification, reference being had to the accompanying drawings, forming a part hereof.

Figure 1 is a perspective view of the body of a bicycle-pump embodying my design. Fig. 2 is a side elevation. Fig. 3 is an edge view.

The novel feature of the design is in the form and appearance of the body of the pump

as a whole, and particularly in the relative arrangement of the parts.

The parts may be enumerated as follows: the base 1, the cylinders 2 2.

What I claim is—

The design of the body of a bicycle-pump substantially as herein shown and described.

In witness whereof I have hereunto affixed my signature, this 19th day of October, 1897, in the presence of two witnesses.

DE WANE B. SMITH.

Witnesses:

PHEBE A. TANNER,
RICH. A. GEORGE.
